GUARD RAIL BRACE

Filed Jan. 21, 1929

UNITED STATES PATENT OFFICE

ALONZO H. WESTON, OF YONKERS, NEW YORK, ASSIGNOR TO AMERICAN CHAIN COMPANY, INC., A CORPORATION OF NEW YORK

GUARD-RAIL BRACE

Application filed January 21, 1929. Serial No. 333,856.

This invention relates to railway track, and more particularly to a type of brace plate for a guard rail.

It has been the practice heretofore to provide braces for guard rails which embraces the outer face of the webs of the guard and traffic rail respectively, and a spacer is wedged between the two rails to maintain the correct clearance for the wheel flanges. The whole device is usually held in adjusted relation by a wedge-shaped locking member driven between the web of the guard rail and the face of the brace, or by some other suitable method well known to the art.

It is also the practice to use a standard rail for a guard rail but, heretofore, it has been necessary to plane off one of the base flanges in order to secure the correct wheel flange clearance between the heads of the rails. On some of the railroads it is also the practice to elevate the head of the guard rail above the head of the traffic rail. This is usually done by using a rail with a deeper web which involves more expense.

It is the principal object of this invention to provide a guard rail brace formed integral with a tie plate which is so shaped as to permit the rail to be secured thereto, either by bolts, rivets or welding in such a manner as to do away with the spacing blocks referred to above.

A further object is to provide a brace which is so constituted that the guard rail is elevated above the traffic rail and can be correctly positioned to give the necessary clearance without planing the base flange.

A clear conception of the construction, operation, and further objects of this invention may be had from the following specification in conjunction with the accompanying drawings, in which

Fig. 1 is an end view of the brace showing the rails in cross-section;

Fig. 2 is a plan view of Fig. 1, partly in cross-section, showing the attaching means on the brace member;

Fig. 3 is an end view of the brace disclosing a modified method of securing the guard rail to the brace;

Fig. 4 is a cross-section through 4—4 of

Fig. 3, taken in the direction of the arrows.

The preferred form of the device as shown in Figs. 1 and 2 comprises a base or tie plate 1 having shoulders 2 and 3 formed integral therewith.

The tie plate is formed with seats at separate levels whereby the guard rail is raised above the level of the traffic rail. The seats 4 and 5 are formed as shown, and traffic rail 6 is positioned on seat 4 with the outer base flange against shoulder 3. The guard rail 7 is positioned on seat 5 with the outer base flange overlapping the inner base flange of the traffic rail 6. This obviates the necessity of planing the flange of the guard rail, as is well known in the art, and provides a holding means for the inner flange of the traffic rail to prevent its tipping. The rail 7 is also positioned in such a manner that the under face of the head and the inner face of the web are in contact with shoulder 2. Shoulder or brace 2 is formed with ears or lugs 8 which extend at right angles thereto and are adapted to contact with the web of the rail as shown in Fig. 2. The lugs 8 are provided with holes 10 for accommodating bolts 11, by which rail 7 is secured to brace 2. A plate or washer 12 is provided for each bolt, which is adapted to conform to the contour of the head, web and flange of the rail, and which is provided with an oval or square hole 9 for gripping the oval or square shank of bolt 11.

The device is assembled as follows:

The tie plate 1 is positioned on a cross-tie 14, and traffic rail 6 is positioned on seat 4, and spikes 15 are driven in to hold the plate 1 and rail 6 in position. Guard rail 7 is now placed on seat 5, having first been drilled with holes corresponding to holes 10 in the lugs 8, and the rail is secured to the shoulder 2 by bolts 11, and spikes 16 are driven in to hold the rail 7 firmly.

Figs. 3 and 4 disclose a modified method of securing the guard rail 7 to the shoulder 2. The rail is set in position and welded to the tie plate 1 at points 17 and to the shoulder 2 at 18, thereby obviating the necessity of drilling holes in the rail 7 for accommodating bolts 11. This greatly simplifies the initial

installation and also does away with the necessity of maintaining the bolts 11.

It is apparent from the above that the device provides a rigid brace member for the 5 guard rail which is easily installed and which will require little, if any, maintenance.

I claim:

1. In a guard rail brace of the type described, a tie plate having a pair of shoulders 10 formed integral therewith, a traffic rail, a guard rail, one of said shoulders being formed to abut the head and web of said guard rail, a pair of lugs formed on said shoulder and conforming with the head and web of said 15 guard rail and means for rigidly securing said guard rail to said shoulder.

2. In a guard rail brace of the type described, a tie plate having a pair of shoulders 20 formed integral therewith, a traffic rail, a guard rail, one of said shoulders being formed to abut the head and web of said guard rail, a pair of lugs formed on said shoulder and conforming with the head and web of said 25 guard rail, said second shoulder abutting the flange of said traffic rail and means for rigidly securing said guard rail to said first mentioned shoulder.

3. In a guard rail brace of the type described, a tie plate having a pair of shoulders 30 formed integral therewith, a traffic rail, a guard rail, one of said shoulders being formed to abut the head and web of said guard rail, a pair of lugs formed on said shoulder and conforming with the head and web of said 35 guard rail and a plurality of bolts for rigidly securing said guard rail to said shoulder.

4. In a guard rail brace of the type described, a tie plate having a pair of shoulders 40 formed integral therewith, a traffic rail, a guard rail, one of said shoulders being formed to abut the head and web of said guard rail, a pair of lugs formed on said shoulder and conforming with the head and web of said 45 guard rail and said shoulder being welded to said guard rail to form a rigid brace.

5. In a guard rail brace of the type described, a tie plate having a pair of shoulders 50 formed integral therewith, a traffic rail, a guard rail, said guard rail overlapping said traffic rail to prevent tipping of said traffic rail and means for securing said guard rail to one of said shoulders.

6. In a guard rail brace of the type described, a tie plate having a pair of shoulders 55 formed integral therewith, a traffic rail, a guard rail, one of said shoulders being formed to abut the head and web of said guard rail, a pair of lugs formed on said shoulder and conforming with the head and web of said 60 guard rail, a plurality of bolts for securing said guard rail to said shoulder, said second shoulder abutting the flange of said traffic rail and said guard rail being seated above 65 said traffic rail and means on said guard rail

for preventing said traffic rail from tipping.

7. In a guard rail brace of the type described, a tie plate having a pair of shoulders 70 formed integral therewith, a traffic rail, a guard rail, one of said shoulders being formed to abut the head and web of said guard rail, a pair of lugs formed on said shoulder and conforming with the head and web of said 75 guard rail, a plurality of bolts for securing said guard rail to said shoulder, said second shoulder abutting the flange of said traffic rail and said guard rail being seated above said traffic rail and the flange of said guard rail overlying the flange of said traffic rail thereby preventing said traffic rail from tipping.

8. In a guard rail brace of the type described, a guard rail, a traffic rail, a tie plate, means formed integral with said plate to elevate said guard rail above said traffic rail in such manner as to permit the flange of said 85 guard rail to overlap the flange of said traffic rail.

9. In a guard rail brace of the type described, a guard rail, a traffic rail, a tie plate, said tie plate being provided with seats so 90 formed as to elevate one rail above the other and to permit the flange of the elevated rail to overlap the flange of the remaining rail to prevent tipping thereof.

In testimony whereof, I have signed this 95 application.

ALONZO H. WESTON.
